UNITED STATES PATENT OFFICE.

AUBIN A. LAFOREST, OF WASHINGTON, DISTRICT OF COLUMBIA.

SWINGING-BARREL COIN HOLDER AND DELIVERER.

1,289,198.

Specification of Letters Patent. Patented Dec. 31, 1918.

Application filed November 10, 1917. Serial No. 201,286.

To all whom it may concern:

Be it known that I, AUBIN A. LAFOREST, a citizen of the United States, residing at Washington, in the District of Columbia, have invented certain new and useful Improvements in Swinging-Barrel Coin Holders and Deliverers, of which the following is a specification.

This invention relates to coin holders and deliverers, and pertains especially to the class of swinging or pivoted coin tubes, barrels or chutes particularly for car conductors' use.

The object of the invention is to provide improvements for facilitating the handling of coins of various denominations so that two or more coins of different denominations will be ejected by one and the same operation in changing coins of various denominations.

A further object of the invention is to provide in a pivoted or swinging barrel coin holder or deliverer, a plurality of swinging or pivoted hand bails or levers for retracting certain of the barrels in pairs, and for retracting the barrels in series of three or more, in coin changing operations.

A still further object of the invention is to provide in a pivoted or swinging barrel coin holder and deliverer, a plurality of finger-pressed levers pivoted in swinging engagement with the barrels for operating the latter in plural sets.

A still further object of the invention is to provide in a coin holder and deliverer, a plurality of coin barrels pivotally mounted on a shaft, a plurality of levers pivoted on said shaft for operating the barrels, and a flat coin chute pivoted on said shaft, and a novel and peculiar means for controlling the exit of coins from the chute.

A still further object of the invention is to provide in a swinging barrel coin holder and deliverer, means for regulating the number of coins ejected from certain of the barrels, and an adjustable ejector of novel and peculiar construction and arrangement.

It has been found that, in operating swinging barrels of coin holders and deliverers separately or independently, too much time is required in making change, for the reason that often two or more of the coin barrels have to be swung separately for making the proper change. It has also been found impractical to manipulate large size coins of certain large denominations in cir-

cular barrels, and to perfect such rapid change making as is advantageous and desirable in this class of changers. Therefore it is the purpose of this invention to overcome the objections and disadvantages of the usual or ordinary changers, and to furnish such novel and peculiar devices as will greatly increase the rapidity in which the barrels are operated and thereby avoid delay owing to separate or independent operation of each barrel.

Various other objects and advantages are attainable in the practical application of the invention.

In the accompanying drawings forming part of this application:

Fig. 1 is a perspective view showing the application of the invention.

Fig. 2 is a sectional view taken on the dotted line A—A Fig. 1.

Fig. 3 is a bottom plan view the dotted lines showing the locking rod in locked position.

Fig. 4 is an enlarged cross section taken on the line B—B Fig. 2, partly broken away, and showing the swinging movement of the flat tube in dotted lines, and the tube coins in dotted lines.

Fig. 5 is a similar view taken on the dotted line C—C Fig. 2, with one pair of barrels retracted.

Fig. 6 is a detail section of one of the barrels.

Fig. 7 is a detail elevation partly broken away, showing the coin-catch tray in open position.

Fig. 8 is a detail perspective view of the tray.

Fig. 9 is a perspective view of a modification.

Fig. 10 is a detail sectional view of one of the barrels shown in the modification.

Fig. 11 is a detail perspective view of the modified adjustable ejector.

Fig. 12 is a detail bottom view showing certain parts of the modification.

The same reference characters denote the same parts throughout the several views of the drawings.

A partly inclosing frame is employed, and comprises a back member 1, having suspending hooks 2, end members 3, a bottom member 4, and a top member 5, provided with a hinged cover 6, having coin slots 6^a. The back and top members of the frame are connected by braces 7 which form partitions

between the coin barrels at the top end thereof, and the bottom of the frame has similar braces 8. The braces 8 have the further function of preventing accidental lateral discharge of coins from the discharge end of the barrels, and the braces 7 have the further function of forming supports for a rod or shaft 9 which extends through the braces 7, and through the ends of the frame, so that 10 the shaft may be withdrawn to receive its mountings, which will now be described.

I have shown in the drawings five coin barrels 10 for coins of various denominations up to the half dollar coin which is 15 separately provided for in a flat coin chute 11. The upper end of each of the barrels is provided with a lug 12 having an aperture for the shaft 9, and the chute 11 has a like lug 13 through which the said shaft 20 extends, whereby the barrels and the chute are loosely pivoted on the shaft for swinging movement. The barrels are held in inclined coin receiving position by plate springs 14 attached to the back of the frame, and a similar spring 15 is provided for the 25 flat chute. The upper ends of the barrels and of the chute are preferably open and are opposite the respective slots 6^a and 9^a in the cover 6. A locking rod 16, having a hand 30 lever 17, is operated against the barrels and the chute for locking them in coin receiving position when desired. The chute 11, has a mouth spring 18 which prevents the coins in the chute from accidental displacement, and these coins are controlled and held within the chute by a coin-stop 11^a, and by a guard 19 extending inwardly from the bottom frame member 4, and projecting 35 partly over the bottom end of the chute, so that when the chute is retracted a coin will 40 pass the guard. The bottom or coin exit end of the barrels has a transverse coin slot 20, and the base of the barrels has a straight edge 21 which engages the front frame member 4 while the edge 22 of the barrels over- 45 laps the edge of the frame member 4, so as to close the exit slot while the barrels are in normal or non-ejecting position. The bottom or base of the barrels has a slot 23 at 50 right angles to the slot 20, to receive an ejector arm 24 secured to the back member of the frame, and projecting forwardly. The barrels are limited or stopped in forward movement by reason of the front end 55 of the slot striking the front end of the ejector arms, which project into the slots 23 in swinging movement of the barrels for ejecting coins, in quantities of one or more. The number of coins ejected from each barrel 60 depends upon the width of the slot 20, and the length of the barrels so as to permit the ejectors to project vertically into the barrels according to the number of coins to be ejected from each barrel, as clearly 65 shown in Fig. 5.

One of the most essential features of my invention is the means for operating two or more barrels jointly so as to simultaneously eject one or more coins from each of the said operated barrels. Said means consist 70 of a plurality of independent hand levers 25, 26 and 27 loosely pivoted on the shaft 9 between the barrel lugs, and dependent from the shaft between the latter and the top frame member 5, into engagement with the 75 front of the barrels so as to leave barrel lengths below the levers for single operation, when desired, independent of said levers. The lever 25 engages two of the barrels. The lever 26 is operated within the lever 27, and 80 against two other barrels, and the lever 27 spans these two barrels and also a third barrel, so that the barrels may be operated in separate pairs, and three barrels, including one of said pair, may be operated by the 85 lever 27 without operating either of the levers 25 and 26. The chute 11 is operated by hand, as usual.

In order to confine the coins ejected by operating the levers 26 and 27, or either of 90 them, I provide the bottom frame member with a coin-receiving tray 28, having side flanges 29, and hinge members 30, for hanging the tray from the back and bottom frame members so that the hinge members 95 30 will engage one of the bottom braces 8 and thereby limit the opening or downward swinging movement of the tray, as clearly shown in Fig. 7 of the drawings. The tray is held in closed position by means of a 100 spring catch 31, which is retracted by hand to permit the trap to swing open upon an inclined position so as to discharge the coins collectively therefrom. The closing movement of the tray retracts the spring 105 31 and permits it to engage the under face of the tray sufficiently to hold the tray in closed position, and the side flanges of the tray prevent the coin from accidental displacement.

The hinged cover 6 affords means for collectively filling and emptying the barrels and the chute when desired or as occasion may demand.

Referring to the modification shown in 115 Figs. 9, 10, 11 and 12, a two barrel coin holder and deliverer is arranged especially for newboys' use, and comprises a shaft or rod 33, pivotally suspending coin barrels 34 and 35, having back springs 36, a locking 120 bar 32, and a lever 37 for operating the barrels. All of said parts are substantially the same as those hereinbefore described, except that the penny barrel 35 has a widened coin discharge opening 38 for the 125 purpose of discharging various number of pennies in change making. The opening 38 may be varied as desired or as occasion may demand, by means of a sleeve 39 slidably mounted on the barrel 35, and having a lip 130

- 40 hooked into a slot 41 of the barrel 35, for limiting the movement of the sleeve. In order to have the ejector 42 coöperate with the sleeve and eject just the number of coins 5 as permitted by the adjustment of the sleeve, I pivot this ejector at 43 to the back 44 of this deliverer, and provide the ejector with grooves or serrations 45 for the free end of a plate spring 46. Obviously this spring 10 will hold the ejector in various adjusted positions as placed by the operator for ejecting coins in multiple or various numbers, such as in changing a five cent piece after deducting one, two or three cents.
- 15 While I have shown and described the invention adapted for conductors' use, obviously it may be otherwise employed for coin holding and changing as desired.

It will be understood that various changes 20 and arrangements of the parts, and of the size and material, number of barrel follower levers and their location, may be made in the practical manufacture of the invention, therefore I do not wish to be understood as 25 limiting myself in these respects, nor in any other respect in keeping with the scope of the appended claims.

Having thus described my invention what I claim as new and desire to secure by Letters Patent is:—

1. In a coin holder and deliverer, the combination with a frame, a shaft fixed in the frame, and a plurality of coin barrels pivoted on and depending from the shaft within 35 the frame, of a plurality of hand levers pivoted on and depending from the shaft and engaging the front of the barrels below the shaft, one of said levers spanning three of the barrels for joint movement thereof, another of said levers hanging within the 40 spanning lever and having free engagement with two of the spanned barrels, and the other of said levers having free engagement with two other barrels for independent 45 movement of the barrels in pairs.
2. In a coin holder and deliverer, a barrel-supporting frame, coin barrels pivotally hung in the frame and having a coin dis-

charge opening in the front adjacent to the bottom thereof, said bottom having an 50 ejector slot centrally under the opening, coin ejectors attached to the back of the frame working in said slot and engaged by the front wall of the barrels for limiting the rearward movement of the barrels, the 55 front edge of said bottom adapted to engage a front member of the frame for limiting the forward movement of the barrels.

3. In a coin holder and deliverer, a frame, a flat coin chute pivoted in the frame and 60 adapted to engage a front member of the frame to limit the forward movement of the chute, a coin stop fixed to the back of the frame and projecting into the chute with the latter in retracted position for suspending 65 coins in the chute, and a coin guard extending inwardly from said frame member for holding coins in the chute with the latter in forward position.

4. In a coin holder and deliverer of the 70 character described, a pair of swingable coin barrels having a coin discharge opening in the front and adjacent the bottom thereof, a hand lever pivoted between the barrels and having free swinging engagement with the front of the barrels for operating the latter jointly in a coin ejecting operation, a sleeve having free sliding movement vertically on one of the barrels for varying the number of coins discharged 80 through said opening, and a spring controlled coin ejector adapted to be adjusted according to the position of the sleeve.

5. In a coin holder and deliverer, the combination with a frame, and coin barrels 85 swingable in the frame, of a coin ejector pivoted to the back of the frame, and a plate spring for holding the ejector in adjusted positions according to the number of coins to be ejected.

In witness whereof I hereunto set my hand in the presence of two witnesses.

AUBIN A. LAFOREST.
